ATTORNEYS

UNITED STATES PATENT OFFICE.

WILLIAM BROAD, OF BEAVER FALLS, PENNSYLVANIA.

ELECTRIC SWITCH.

Application filed March 26, 1921. Serial No. 455,722.

To all whom it may concern:

Be it known that I, WILLIAM BROAD, a citizen of the United States, and a resident of Beaver Falls, in the county of Beaver 5 and State of Pennsylvania, have invented a new and useful Improvement in Electric Switches, of which the following is a specification.

The invention relates to electric switches, 10 and the object thereof is to provide a switch of simple and inexpensive construction, particularly suitable for controlling circuits carrying small currents.

The invention is illustrated in the accompanying drawings, of which Figs. 1 and 2 are plan views of two forms of switches embodying the invention; Figs. 3 and 4 side views of the switches shown, respectively, in Figs. 1 and 2; Fig. 5 a combined section 20 and elevation of electric massage vibrator illustrating a use of the switch; and Fig. 6 a sectional view to enlarged scale taken on the line VI—VI, Fig. 5.

In the practice of the invention a base 25 plate of insulation is provided with a pair of terminals insulated from each other by the plate. The terminals are normally urged toward contact with each other to close the switch, and a finger of insulating material 30 is mounted on the plate in such manner that it may be moved to and from a position in which it separates the normally contacting terminals.

In the embodiment of the invention illustrated in Figs. 1 and 3, the insulation base comprises a plate 1 of fiber board. To such board there are attached thin conducting plates 2 and 3 forming switch terminals. The terminal plate 3 is provided with a 40 resilient arm 13 normally urged toward contact with the plate 2 to close the switch. To open the switch a finger 4, which may also be formed of a strip of fiber board, is pivoted at 5 to the base plate 1. When finger 4 is in the position indicated in dotted lines 45 it lies between the end of arm 13 and terminal plate 2, separating such arm from the plate so that the switch is open. When finger 4 is in its full line position, arm 13 50 is, by reason of its resiliency, in contact with plate 2 to close the switch.

The embodiment of the invention illustrated in Figs. 2 and 4 differs from that just described in that finger 4^a is provided with 55 a lug 6 arranged over the top of resilient arm 13^a. When finger 4^a is in circuit open-

ing position indicated in dotted lines, lug 6 rests upon the face of arm 13^a at a position far enough from the end of such arm that finger 4^a may readily separate the end of 60 the arm from plate 2^a. When the finger is in its full line position, lug 6 bears upon the end of arm 13^a and positively holds it in contact with plate 2^a, thus rendering the closing of the switch independent of the 65 resiliency of arm 13^a.

In both forms of the switches, the terminals may be provided with small bendable strips 7 to which the ends of circuit conductors may be soldered or otherwise 70 electrically connected.

While the switch may be used in various places where it is desirable to control a circuit carrying a small current, it finds particular applicability to massage vibrators 75 such as illustrated in my Patent No. 1,197,-338. Figs. 5 and 6 show a massage vibrator of this type provided with a switch of the form illustrated in Figs. 2 and 4. The vibrator comprises a casing 8 in which there 80 is mounted an electro-magnet 9 adapted to be energized by an alternating current. A spring 15, fixed at one end, is arranged within the casing adjacent to the end of the electro-magnet, and has attached to it an 85 armature 10 adapted to be intermittently drawn toward the electro-magnet as it is intermittently energized. The free end of the spring is provided with an applicator 11 of any desired form. 90

In massage vibrators of this type, the armatures are wound with fine wire which carries small currents. That the circuit through the magnet may be opened and closed conveniently, a switch of the form 95 shown in Figs. 2 and 4 is mounted within casing 8 in such position that finger 4^a projects through a slot 12 formed in the side of the casing. The ends of the slot form abutments defining the limits of the movements 100 of finger 4^a in its alternate circuit opening and closing positions. In use, the operator may readily move finger 4^a to one position or the other, depending upon whether it is desired to initiate or stop the operation of 105 the vibrator.

The switch is simple in construction, economical to manufacture, and current is not caused to flow through rivets, hinges, or like connections, which are likely to loosen when 110 subjected to vibration. In its operation, the circuit controlling finger wipes the contact-

ing surfaces of the terminals and, therefore, keeps them free from foreign matter such as dust or corrosion.

According to the provisions of the patent statutes, I have described the principle and operation of my invention, together with the construction which I now consider to represent the best embodiment thereof. However, I desire to have it understood that, within the scope of the appended claim, the invention may be practiced by other forms of construction than that specifically shown and described herein.

I claim:

15. An electric switch, comprising a base plate of insulation, a pair of terminals mounted

on said plate, one terminal being provided with a resilient arm normally urged toward contact with the other terminal to close the switch, and a finger of insulating material pivoted to said base plate and movable to a position between said terminals to open the switch, said finger being provided with a lug movable over the face of said arm to positively hold the arm in circuit closing position when said finger is moved from its position between said terminals.

In testimony whereof, I have hereunto set my hand.

WILLIAM BROAD.

Witness:

EDWIN O. JOHNS.
